UNITED STATES PATENT OFFICE.

THOMAS GOODMAN, OF MELROSE PARK, ILLINOIS.

BASEBALL MASK.

Application filed March 6, 1922. Serial No. 541,808.

To all whom it may concern:

Be it known that I, THOMAS GOODMAN, a citizen of the United States, residing at Melrose Park, in the county of Cook and State 5 of Illinois, have invented certain new and useful Improvements in Baseball Masks, of which the following is a specification.

This invention relates to masks of the character worn by baseball players, and the 10 main object of the invention is to provide an improved mask characterized by lighter weight, increased comfort, and greater facility of manipulation than the masks at present used, without any sacrifice of strength 15 and efficiency.

In baseball masks of the known and commonly used type, the body of the mask comprises a welded wire frame which, in order 20 to have the requisite strength and rigidity to withstand the severe blows and concussions to which it is often subjected, is made of heavy wire, and, when equipped with the necessary padding, is objectionably heavy on the head of the wearer. In designing the 25 mask of my present invention, I have had mainly in view a substantial reduction in the weight of the mask without any sacrifice of its protective quality; and with this in view, I have discarded the common welded wire frame and employed in lieu thereof a one piece metal body or frame, preferably 30 of a light cast metal, such as aluminum; and to secure a still better combination of strength and lightness, I also employ special 35 structural features, such as weight reducing slots at points least subject to strain and strengthening ribs located in regions which are most liable to breakage or deformation, which ribs also serve in large measure to 40 protect the envelope of a ball from being cut by impact with the mask.

These and other objects and attendant advantages of the invention will be apparent to persons skilled in the art as the same becomes better understood by reference to the 45 following detailed description, taken in connection with the accompanying drawings wherein I have illustrated a practical and preferred embodiment of the invention, and 50 in which—

Fig. 1 is a front elevation of the cast metal frame of the mask;

Fig. 2 is a perspective elevation of the same as seen from the right of Fig. 1;

Fig. 3 is an enlarged sectional detail on the line 3—3 of Fig. 1;

Fig. 4 is a front elevation of the complete mask, including the padding and fastening straps and mask holding bands; and

Fig. 5 is a perspective elevation of Fig. 4 60 as viewed from the right of the latter figure.

Referring to the drawings, 5 designates as an entirely the cast metal frame or body, having the general outline contour of the human face, and preferably made of aluminum, in order to combine lightness and strength.

The marginal portion of the frame, to which the padding is attached, is outwardly flared, as indicated at 5^a; and the frame may 70 be further lightened without any sacrifice of strength by forming at spaced intervals throughout the flared marginal portion slots 6.

Across the front of the frame in the region of the eyes is a continuous wide vision slot 7, and below the latter in the region of the mouth is a substantially rectangular expectoration slot 8, the edges of the latter being preferably oblique as shown. By giving 75 the expectoration opening this form, there is less weakening of the metal than where the upper and lower edges of the expectoration opening lie parallel with the lower edge of the long vision opening. 80

Parallel with and slightly inwardly of the upper and lower edges of the vision opening 7 are protuberant ribs 9, preferably formed by offsetting the metal of the frame, in the casting operation, as indicated in Fig. 90 3. From the center of the upper rib 9 there extends upwardly a similar vertical rib 10.

Similar ribs 11 are formed adjacent to the margins of the expectoration opening 8. The margins of the latter opening and the 95 relatively long upper and lower margins of the vision opening are the weakest and most vulnerable points of the mask frame with reference to the effects of blows and concussions, and the described ribs very effectively reinforce the mask against breakage or deformation in these regions. Accidental cracking or breaking of the crown of the mask is also strongly resisted by the vertical rib 10. The protuberant ribs 9 and 11 100 bounding the margins of the vision and expectoration openings serve another valuable purpose in that they are sufficiently close to the edges to receive the impact of a ball on their rounded surfaces and prevent the cover 110 or envelope of the ball from being cut or scored by the sharp edges of the openings.

Opposite the lower portion of the opening 8 I preferably form slots or openings 12 which further lighten the frame and increase the ventilation in the region of the 5 chin.

Inwardly of the slots 6 are formed a group of slots 13 through which extend leather fastening strips 14 that are attached to the face pad 15 and are united to similar 10 fastening strips 16 extending over the rear edge of the frame by lacings 17. The chin pad 18 is similarly attached to the frame by fastening strips or corner portions 19 of the chin pad envelope passed through the 15 slots 20 in the lower portion of the frame and connected to similar attachment strips or corner portions 21 overlapping the edge of the frame by cords 22.

At points opposite the ends of the vision 20 opening 7 are slots 23, and above the central rib 10 are a pair of parallel slots 24, through which slots extend side and top straps 25 and 26, respectively, to which are attached the broad elastic horizontal and vertical 25 bands 27 and 28 by which the mask is held in position on the face of the wearer, with capacity for quick dislodgment, when necessary, by throwing the mask upwardly and backwardly by a push on the chin cushion 30 or pad 18.

It is believed that the structural features and advantages of my improved mask will be apparent from the foregoing without further detailed description. The customary 25 wire frame mask equipped with padding and fastening straps weighs two pounds. My improved mask as herein shown and described, fully equipped with padding and fastening straps, and with the 40 frame of aluminum weighs one pound, and possesses fully the strength and efficiency of the wire frame mask. Structurally it is easier to manufacture and assemble than the wire frame mask, since the entire frame 45 may be formed in a single casting operation, doing away with the necessity of spot welding the large number of intersecting and meeting wire elements.

Although I have shown and described the 50 body or frame of the mask as of cast metal, it will be evident that the same may be formed of a heavy sheet metal pressed to shape in suitable dies.

I claim.

1. A one-piece metal frame for base ball 55 masks formed with vision and expectoration openings therein and with strengthening ribs skirting the margins of said openings, said ribs lying sufficiently close to said margins to receive the impact of a ball and protect the envelope of the latter from being cut by the edges of said openings.

2. A one-piece metal frame for baseball 60 masks formed with a single wide vision opening extending across the nose and eye areas of the mask and with protuberant stiffening ribs adjacent to and parallel with the upper and lower edges of said opening, and disposed sufficiently close to said margins to receive the impact of a ball and protect the envelope of the latter from being 65 cut by the edges of said opening.

3. A one-piece metal frame for baseball 70 masks formed with a single wide vision opening extending across the nose and eye 75 areas of the mask and with protuberant stiffening ribs adjacent to and parallel with the upper and lower edges of said opening and a central stiffening rib extending upwardly from and at right angles to the uppermost of said first-named stiffening ribs.

4. A one-piece metal frame for baseball 75 masks formed with a substantially rectangular expectoration opening the four edges of which are oblique to lines bisecting said opening lengthwise and widthwise of said frame and with protuberant stiffening ribs disposed adjacent to and substantially parallel with the opposite side edges of said 80 opening.

5. A one-piece metal frame for baseball 85 masks formed with a single wide vision opening extending across the nose and eye areas of the mask and with a substantially 90 rectangular expectoration opening located centrally between said vision opening and the chin portion of the mask and having its four edges oblique to lines bisecting said opening lengthwise and widthwise of said frame, and protuberant stiffening ribs adjacent to and parallel with the upper and lower edges of said wide vision opening and similar ribs adjacent to and substantially 95 parallel with the opposite side edges of said expectoration opening.

THOMAS GOODMAN.
